VENTILATED WATER CLOSET

Farris E. Dixon, Louisville, Ky., assignor to American Radiator & Standard Sanitary Corporation, New York, N.Y., a corporation of Delaware
Filed Dec. 3, 1962, Ser. No. 241,588
7 Claims. (Cl. 4-215)

This invention relates to a device for ventilating a water closet and more particularly to a device for removing foul air from adjacent the bowl of a water closet.

An object of the invention is to provide a ventilating device for a water closet or toilet which will operate reliably and which has a minimum of moving parts.

Another object is to provide a ventilating system having a minimum of potential trouble spots which would adversely affect its operation.

Another object is to provide a ventilating system which is substantially trouble free.

Another object is to provide a ventilating system which is adaptable for use either with a water closet having a tank or with a tankless water closet.

Another object is to provide a ventilating system which is hydraulically operated and which requires minimum quantities of water for operation.

Another object is to provide a water closet having a ventilator wherein the water closet can be flushed without operating the ventilator.

Another object is to provide a ventilating system in which a liquid seal is established between an air discharge tube and the toilet bowl when the ventilating system is not operating.

Another object is to provide a ventilating system which will prevent passage of air from within the water closet tank to the air discharge tube.

Another object is to provide a water closet having a ventilating system in which communication between the water closet water supply conduit and the ventilator discharge tube is prevented in the event that a negative pressure occurs in the water supply conduit.

Other objects and features of the invention will appear as the description of the particular physical embodiments selected to illustrate the invention progresses.

For a better understanding of the present invention, reference should be had to the accompanying drawings, wherein like numerals of reference indicate similar parts throughout the several views and wherein:

FIGURE 1 is a schematic view of a water closet ventilating system illustrating the principles of operation of the present invention.

FIGURE 2 is a partial schematic view of a water closet illustrating the relationship between the passage in the toilet bowl housing and the ventilator tubes shown in FIGURE 1 wherein the discharge from the ventilating system is led to a location below the toilet bowl water seal.

FIGURE 3 is a partial schematic view similar to FIGURE 2 but modified to show the discharge from the ventilating system being led to a location above the toilet bowl water seal.

FIGURE 4 is a schematic view of a ventilating system similar to that of FIGURE 1 but modified so that it can be used on a tankless water closet.

FIGURE 5 is a perspective view of a water closet in which a modified form of the ventilating system shown in FIGURE 1 is installed.

FIGURE 6 is an elevation, partly in section, of the water closet of FIGURE 5.

FIGURE 7 is a front view, partly in section, of the flush tank of FIGURE 5 showing the flush valve and the ventilating system installed therein.

2

FIG. 8 is a plan view of FIGURE 7 with the flush tank cover removed.

FIGURE 9 is a partial section taken along the line 9-9 of FIGURE 8.

FIGURE 10 is a front view, partly in section, of the ventilating system shown in FIGURE 7.

FIGURE 11 is a sectional view taken along the line 11-11 of FIGURE 12.

FIGURE 12 is a sectional view taken along the line 12-12 of FIGURE 10.

FIGURE 13 is a partial sectional view taken along the line 13-13 of FIGURE 11.

FIGURE 14 is a partial perspective and schematic view of an embodiment similar to that of FIGURES 5-13 showing the path and location of water when the ventilator is in operation.

FIGURE 15 is a perspective and schematic view of an embodiment similar to that of FIGURES 5-13 showing a water seal which is used to prevent passage of air from the tank to the ventilator discharge tube.

FIGURE 16 is a schematic view of an alternate embodiment wherein the high vacuum-low volume section of the aspirator is mounted in the discharge tube.

FIGURE 17 is a plan view of the high vacuum-low volume section of the aspirator of FIGURE 16.

FIGURE 18 is an elevational view of the high vacuum-low volume section of the aspirator shown in FIGURE 17.

Referring to the drawings, FIGURE 1 illustrates schematically the principle of operation of the ventilating system of the present invention. The ventilating system of FIGURE 1 may be installed in a water closet flush tank 10, shown partially in FIGURE 2, mounted conventionally at the top rear portion of a toilet bowl 12.

The ventilation system in FIGURE 1 utilizes a flush tank overflow tube which is conventionally provided in water closet flush tanks to protect the flush tank against filling above a predetermined level. Thus as shown in FIGURE 1, the ventilating system comprises an overflow tube 14 which is in communication with a hollow passageway 15 extending around the rim of the toilet bowl 12, a ventilator discharge tube 16 in communication with the toilet bowl waste passageway 22 and a U-shaped tube 18 serving as a water seal between the two tubes 14 and 16 for sealing the discharge tube 16 from the atmosphere.

Thus it can be seen from FIGURES 1 and 2 that when there is no water in the U-shaped tube or seal 18, communication is provided between the passageway 15 in the rim of the toilet bowl 12 and the toilet bowl waste passageway 22, so that air adjacent the openings 20 in the toilet bowl rim passageway 15 can be discharged to waste. Means are provided for filling and evacuating the seal 18 with water so that communication between the overflow tube 14 and discharge tube 16 is cut off when the ventilating system is not operating thereby sealing the discharge tube 16 from the atmosphere. This means consists of an aspirator which is used for evacuating water from the seal 18 and which is also used for creating a reduced pressure in the discharge tube 16 to cause air to flow from the passageway 15 in the rim of the toilet bowl to the discharge tube 16 to waste as set forth heretofore.

The aspirator comprises a high vacuum-low volume section 24 for evacuating water from the seal 18 and a low vacuum-high volume section 26 for creating the reduced pressure in the discharge tube 16. The terms high and low vacuum and volume are used merely to denote the relative operating characteristics between the two aspirator sections. The aspirator is operated by utilizing the water supply line provided for flushing the water closet.

In the high vacuum-low volume section 24 of the

aspirator, a conduit or tube 28 of smaller diameter than the discharge tube 16 is provided at the upper portion of the discharge tube 16 so that as water flows therethrough, suction will be created in the smaller diameter conduit 30 leading laterally from the tube 28 as is well known.

The laterally extending conduit 30 is in communication with an elevated water seal reservoir 32 while the latter is in communication with the lower portion of the U-shaped seal tube 18 by means of conduit 31. Thus, when the aspirator is operated, the water in the seal 18 will be drawn up into the reservoir 32 due to the suction provided by the high-vacuum section 24. The water will remain in the reservoir 32 and will not be drawn into the aspirator since the difference between the pressure in the lateral conduit 30 created by the high-vacuum section 24 and the pressure in the seal tube 18 created by the low vacuum section 26 (to be described hereinafter) is not sufficient to carry over the water to the high pressure aspirator section 24.

As the high vacuum section 24 continues to operate, however, it will draw up air from the seal 18, such withdrawn air bubbling up through the water in the reservoir 32 as illustrated in FIGURE 1. As the water flow to the aspirator is stopped and no further suction is produced thereby, the water in the reservoir 32 will flow back by gravity to establish the seal 18 thereby sealing the discharge tube 16 from the atmosphere.

The low vacuum section 26 of the aspirator which operates with the same water used for operating the high vacuum section 24, makes use of the discharge tube 16 so that the water flowing from the smaller diameter tube 28 of the high vacuum section 24 will flow into the larger diameter discharge tube 16 to create a suction in the discharge tube 16 to draw air from the laterally extending seal tube 18.

It is believed apparent, therefore, that as water flows to the aspirator, the water in the seal 18 will be drawn to the reservoir 32 while the suction created in the discharge tube 16 will cause air to be drawn from the area adjacent the toilet bowl rim to the overflow tube 14, seal 18, and discharge tube 16, to be discharged to waste along with the water used for operating the aspirator. An overflow cap 33 having a downwardly depending flange 35 portion extending below the normal water level of the flush tank 10 is mounted on top of the overflow tube 14 and serves to prevent air from being drawn from within the flush tank 10 into the ventilator system.

The ventilator is placed in operation by opening an actuating valve 34 in the water supply line 36. A vacuum breaker 38 and a water seal 40 may be provided in the water supply line 36 to eliminate the possibility of drawing sewer gases from the discharge tube 16 into the water supply line 36 in the event that a negative pressure should develop in the water supply line 36 with the actuating valve 34 in an open position.

A water refill tube 42 leading from the flush water inlet valve, (not shown in FIGURE 1) supplies water to the seal 18 when the water closet is flushed while a difference in elevation, denoted by "a" in FIGURE 1, between the inlet and outlet of the seal 18 is provided to direct refill water to the toilet bowl seal 44 via the overflow tube 14, the rim passageway 15, and openings 20 after the seal 18 is filled to the level indicated by "b" in FIGURE 1.

The means for controlling the operation of the ventilator and its operating relationship relative to the flushing mechanism will be described hereinafter with reference to the embodiment of FIGURES 5-13.

In the embodiment of FIGURE 2, the discharge tube 16 is shown as communicating with a separate discharge passageway 46 provided in the toilet bowl housing 12 wherein such passageway 46 is shown as communicating with the waste outlet 22 of the toilet bowl at a location below the bowl water seal 44.

In a modification shown in FIGURE 3 the discharge tube 16 exists into the toilet bowl waste passage 22a at a location above the bowl water seal 44a. In certain types of toilet bowls where the bowls is flushed with a siphoning action in the waste passageway leading from the bowl, the use of the arrangement shown in FIGURE 2, where the mixture of air and water in the discharge tube 16 communicates with the toilet bowl waste outlet at a location below the bowl water seal 44, is preferable since it would not be critical that the ventilator seal 18 be established before the siphoning action of the flushing toilet bowl occurs. Thus, in the embodiment of FIGURE 3, if the ventilator seal 18 was not established before the siphon action of the bowl occurs as it is flushed, the discharge tube 16 would be open to atmosphere and thus tend to adversely affect the siphoning action of the bowl as it is flushed. This would not happen in the embodiment of FIGURE 2 since the discharge tube 16 is in communication with the toilet bowl waste passage 22 at a location below the toilet bowl water seal 44.

The ventilator system according to the present invention may be installed in the flush tank 10 shown in FIGURES 2 and 3 or alternatively, it may be used with a tankless toilet as shown in the modification of FIGURE 4. In that modification, since there is no flush tank, a tank overflow tube such as the tube 14 in FIGURE 2 is not provided. However, a water supply tube 14a is employed which corresponds to the overflow tube 14 of FIGURE 2.

The principle of operation of the ventilator system of FIGURE 4 is essentially the same as that of FIGURE 1. Thus, in one position (flush position) of the flush valve handle 48, the toilet bowl 12a will be flushed by admitting water through the flush valve 50 to the rim passageway 15 of the toilet bowl 12a through the water supply tube 14a. At the same time water will be admitted to the seal tube 18 through the refill tube 42a to insure that the seal 18 is established. In another position (ventilate position) of the flush valve handle 48, water will be admitted from the flush valve 50 to a tube 43 for operating the aspirator which in turn evacuates water from the seal 18 and draws the air through the openings 20 in the rim passageway 15 of the toilet bowl 12a to waste as herebefore set forth. When the flush valve handle 48 is returned to its initial shut-off position, the aspirator is shut off and the seal 18 is established as hereinbefore set forth. The ventilating system and flush valve shown in FIGURE 4 may also be used with the toilet bowl 12 of FIGURE 2.

In the embodiment of FIGURES 5 to 13 flush tank 10 is shown in FIGURE 5 as mounted in its conventional rearward position relative to the toilet bowl 12b. The tank 10 contains the water for flushing the toilet in the conventional manner and houses the ventilating system and the flushing mechanism. The flush tank 10 is normally filled to a level as shown in FIGURE 7 so that when the flush valve 52 is lifted from its seat 53, the water in the tank 10 will pass to the conduit 54, to the rim passageway 15b to flush the toilet. The flush valve 52 is mounted for pivotal movement about the end of an upstanding arm 56 such that when the external operating handle 58 is turned counter clockwise, it will rotate an actuating arm 60 in a counter clockwise direction. A suitable linkage such as a chain 61 is provided between the end of the actuating arm 60 and the container 63 of the flush valve so that counter clockwise rotation of the operating handle 58 will pivot the flush valve 52 off of its seat 53. After the water in the tank 10 flows by gravity to the toilet bowl 12b through the unseated flush valve 52, the flush valve 52 will reseat itself and the tank 10 will be filled up with water supplied through a water supply conduit 62. A valve 64 operated by a float 65 admits and shuts off water to the tank 10 in the conventional manner.

The above described flushing mechanism per se does not form part of the invention but is shown and briefly described merely to show its operational and constructional orientation relative to the ventilating system. Therefore, it is to be understood that other types of flushing mechanisms may be employed with the ventilating system of the present invention.

The ventilating system shown in FIGURES 5 to 13 operates essentially on the same principles as that described and shown in FIGURE 1, with some modifications. In FIGURES 5-13, for example, certain elements have been constructed, grouped together, and arranged in a different manner for the sake of convenience, and an overflow trap 72 (to be described hereinafter) is used instead of the cap 33 shown in FIGURE 1.

Thus in the embodiment of FIGURES 5-13 the overflow tube is shown at 14b, the discharge tube at 16b, and the water seal 18b between the two is shown as comprising a U-shaped conduit having two legs 67 and 68 and a cross-over conduit 70 (FIGURE 11) having one end connected to the upper end of the discharge tube 16b and the other end to the upper portion of the legs 68 of the seal 18b. A cross-over conduit 71 is also provided for connecting the upper end of the overflow tube 14b to the upper portion of the leg 67. With this arrangement the overflow tube 14b may be centrally located in the flush tank 10 with the seal 18b on one side and the discharge tube 16b and overflow water seal 72, to be described hereinafter, on an opposite side to provide a balanced unit which will conveniently fit into the flush tank 10. Details of the overflow water seal 72 have not been shown in FIGURES 7, 8, 10 and 11 since it is shown in detail in FIGURES 14 and 15.

As can best be seen in FIGURE 11, the conduits 67, 68, 70, 71, and 72 may be formed as an integral unit for mounting on the overflow tube 14b and discharge tube 16b by means of the tube portions 73 and 74. The water seal reservoir 32b is mounted on one side of the two cross-over conduits 70 and 71, as can best be seen in FIGURE 13, and the conduit 31b between the reservoir 32b and the water seal 18b may be made integral with the reservoir 32b as can best be seen in FIGURES 10 and 12.

The high vacuum section 24b of the aspirator may be mounted on top of the cross-over tube 70 and directly over the discharge tube 16b so that the water discharging therefrom will pass directly into the low vacuum section 26b of the aspirator.

As can best be seen in FIGURE 9, the high vacuum aspirator comprises a housing 75 having a passageway 76, therein so that water flowing through the passageway 76 from the water supply line 36b will create a suction in the reduced diameter lateral passageway 77 for drawing air from the reservoir 32b via the conduit 30b. As the water leaves the high vacuum section 24b of the aspirator it is sprayed into the discharge tube 16b, as best shown in FIGURE 11, thereby creating a suction in the laterally extending crossover tube 70 for drawing air from adjacent the rim of the toilet bowl 12b as hereinbefore set forth with reference to the description pertaining to FIGURE 1. The water spraying past the high vacuum section 24b of the aspirator down the center of the discharge tube 16b will be sufficient to move an adequate amount of air from the rim of the toilet bowl. The mixture of water from the aspirator and the withdrawn air from adjacent the toilet bowl passes down the discharge tube 16b and externally of the flush tank 10 to the toilet bowl waste passage.

The refill tube 42b (FIGURES 7 and 8) for supplying water to the seal 18b when the flush valve 64 is open enters the leg 67 of the seal 18b by a connection 80 (FIGURE 10) at a location below the normal water level of the flush tank 10 to insure that the seal 18b will fill even if the refill tube 42b is inadvertently disconnected from the seal 18b since, in such an event, water from the tank

10 would then replenish the seal 18b through the opening of the connection 80.

The principle of operation of the ventilating system shown in the embodiment of FIGURES 5-13 is similar to that shown schematically in the embodiment of FIGURE 1, so that a detailed account of the operation of the embodiment of FIGURES 5-13 is not believed necessary. FIGURE 14, however, which is a schematic representation of the embodiment of FIGURES 5-13, illustrates the path and location of air and water when the ventilator is in operation. Thus the path of air from the overflow tube 14b through the seal 18b and cross-over tube 70 to the discharge tube 16b can be clearly seen along with the seal water being contained in the reservoir 32b.

FIGURE 14 also illustrates the overflow trap 72, mentioned heretofore, as comprising a U-shaped conduit having two legs, one leg 81 being open at the top for communication with the interior of the flush tank 10 and another leg 82 being connected to the cross-over 71. The overflow trap 72 is preferred over the cap 33 shown in FIGURE 1 since when the trap 72 is filled with water, it will prevent passage of air from within the flush tank 10 to the discharge tube 16b as the aspirator is in operation even if the level of the water in the flush tank 10 is well below normal. This overflow trap 72 also permits normal overflow of flush tank water to the overflow tube 14b if the level of water in the flush tank 10 rises to an abnormal height.

FIGURE 15, which is a more detailed schematic representation of the overflow trap 72 shows a channel 84 extending between the leg 67 of the seal 18b and the leg 82 of the overflow trap 72. This channel 84 is at a lower elevation than the top opening or mouth of the overflow tube 14b so as to provide the overflow trap 72 with water from the main seal 18b after the main seal 18b is filled by the refill conduit 42b as can be clearly seen in FIGURE 15.

With the construction and arrangement of the main seal trap 18b, the overflow trap 72, the overflow tube 14b, and the discharge tube 16b as illustrated, the ventilating system will utilize all of the refill water without wasting any down the discharge tube 16b. Thus, the sequence of events which occurs when the refill water is flowing through refill conduit 42b is as follows: refill water fills the main trap 18b, excess water then flows into the overflow trap 72 via the channel 84, excess water then flows down the overflow tube 14b to provide water from the toilet bowl water seal 44b (FIGURE 6).

The ventilator is placed in operation by raising (rotating in a clockwise direction as viewed in FIGURE 7) the operating handle 53 which in turn opens the ventilator actuating valve 85 by means of the lever 86 (FIGURE 8), for supplying water to the aspirator through the conduit 36b. Thus, it can be seen in FIGURE 8 that when the operating handle 53 is raised, the valve 85 will be opened and the ventilating system will be placed into operation. When the handle is lowered, the valve 85 will be closed to shut off the ventilating system while at the same time the lowering of the handle will trip the flush valve 52 by means of the lever 60 and chain 61. If it is desired to flush the toilet without ventilating, it is only necessary to move the handle downwardly, that is rotate it in a counterclockwise direction as viewed in FIGURE 7. Thus, the water closet can be flushed without turning the ventilator on.

In a modification of the invention, the high vacuum-low volume section of the aspirator is mounted in the discharge tube such as shown schematically in FIGURE 16. The details of such a high vacuum aspirator section 24c are shown in FIGURES 17 and 18.

The aspirator section 24c may be inserted between an upper portion 16d and a lower portion 16e of the discharge tube. The lower end of the aspirator section 24c is shown in FIGURE 18 as having a flange 90 mating

with a flange 91 on the portion 16e of the discharge tube while fastening means such as the screws 92 serve to secure the flanges 90 and 91 together. A sealing gasket 93 may be provided between the flanges. The upper end of the aspirator section 24c may be secured to the upper portion 16d of the discharge tube by extending an end thereof into the aspirator section 24c and cementing the connection therebetween.

The aspirator section 24c comprises a conduit section 89 and a member 94 extending therein having a water inlet passageway 95 and a passageway 96 in which a suction is created in much the same manner as shown and described with reference to the embodiment of FIGURE 7. The member 94 extends into the conduit section 89 but does not prevent communication therethrough so that the portions 16d and 16e of the discharge tube communicate with one another. Suitable strengthening ribs 97 and 98 may be provided in the aspirator section 24c.

It is believed apparent from the above description that the invention is shown and described as embodying a ventilating system which is hydraulically operated and which has a minimum of mechanical parts so that the maintenance required and the potential trouble spots are at a minimum. Component parts may be combined and preformed to facilitate construction and the entire assembled unit will conveniently fit into a standard size flush tank without impairing the operation of the flushing mechanism while the water closet may be flushed without placing the ventilating system into operation. The ventilating system does not evacuate the flush tank even if the water level in the flush tank is well below normal. The discharge tube of the ventilating system is always sealed off from the atmosphere when the ventilating system is not in operation and the discharge tube will also be sealed off from the water supply line in the event that a negative pressure should develop therein when the ventilator water supply valve is open. There is no waste of refill water used in the ventilating system while provision is made to seal off the discharge tube from atmosphere even if the main seal trap water supply line is inadvertently disconnected. The ventilating system may be used either in connection with a toilet bowl having a flush tank or a tankless water closet. The ventilating component parts may be constructed of relatively inexpensive materials such as plastic and component parts may be formed as integral units to reduce the cost of construction. The ventilating system is easy to install since it may be preformed before it is installed to the water closet.

It is to be understood that the invention hereinabove described is not limited in its application to the details of construction and arrangement of parts illustrated in the accompanying drawings, since the invention is capable of other embodiments and of being practiced or carried out in various ways. Also it is to be understood that the phraseology or terminology employed in the specification is for the purpose of description and not of limitation.

The invention hereinabove described may be varied in construction within the scope of the claims, for the particular device selected to illustrate the invention is but one of many possible embodiments of the same.

What is claimed is:

1. In a water closet having a bowl, a flush tank, and an overflow tube providing communication between the flush tank and the bowl, the improvement comprising, a discharge tube in said flush tank, a U-shaped ventilator water seal providing communication between said overflow tube and said discharge tube, an upright U-shaped overflow seal trap for preventing the passage of air from inside said flush tank into said overflow tube, said overflow seal trap having one leg in communication with the interior of said flush tank said overflow seal trap and dis-

charge tube being on one side of said overflow tube and said U-shaped ventilator water seal being on an opposite side, a first crossover conduit between one leg of said U-shaped ventilator water seal and said discharge tube, a second crossover conduit between the other leg of said U-shaped water ventilator seal and the other leg of said overflow seal trap, said second crossover conduit being in communication with the mouth of said overflow tube and having conducting means at a lower elevation than the mouth of said overflow tube such that when said U-shaped water ventilator seal is filled, water will flow through said conducting means to fill said upright U-shaped overflow seal trap and thereafter flow to the mouth of said overflow tube, and aspirator means communicating with said discharge tube and operable upon activation to simultaneously withdraw water from said U-shaped water ventilator seal and to produce a reduced pressure in said discharge tube to withdraw air from said bowl, and means for activating and deactivating said aspirator means whereby upon deactivation the U-shaped water ventilator seal between the overflow tube and discharge tube is established.

2. In a water closet as set forth in claim 1 wherein said first and second crossover conduits, said overflow seal trap, and said U-shaped ventilator water seal are formed as an integral unit.

3. In a ventilating system for a water closet, the combination comprising, a discharge conduit in the flush tank of said water closet, conduit means providing communication between said discharge conduit and the bowl of said water closet, water seal means in said conduit means, first aspirator means communicating with and operable to withdraw water from said water seal means to establish communication between said water closet bowl and said discharge conduit via said conduit means, said first aspirator means comprising an aspirator and an enclosed reservoir arranged such that said aspirator when in operation produces a reduced pressure in the enclosed reservoir so that water from the water seal means is thereby drawn into and temporarily stored in the reservoir, second aspirator means communicating with and operable to produce a reduced pressure in said discharge conduit to draw air from said bowl through said conduit means and discharge same to said discharge conduit when said water is withdrawn from said water seal means and temporarily stored in said reservoir, and means controlling said aspirators whereby upon reactivation thereof water flows by gravity from the reservoir to said water seal in the conduit means to establish the water seal.

4. In a ventilating system as set forth in claim 3 wherein said first and second aspirator means are arranged in a series relationship such that both aspirators operate with the same flow of liquid.

5. In combination with a ventilating system for a water closet having a water seal between the ventilator system inlet and outlet, the combination comprising an enclosed reservoir carried at an elevation extending above the operating level of said water seal, conduit means communicating between the reservoir and the water seal, aspirator means communicating with said reservoir and operable to produce a reduced pressure in said reservoir such that water is drawn into the reservoir from said water seal via said conduit means and temporarily stored in the reservoir when said aspirator is activated, said conduit means conducting water from the reservoir to the water seal to establish the latter by gravity flow upon deactivation of said aspirator.

6. In combination with a ventilating system for a water closet, the combination comprising a discharge conduit in the water closet flush tank, an overflow conduit in said flush tank communicating with a seal trap in the water closet bowl, a ventilator seal in said flush tank between the discharge conduit and said overflow conduit, operable means in communication with and operable upon activation to

withdraw water from said ventilator seal and to permit return of water to said ventilator seal upon deactivation, an overflow seal means in said flush tank preventing communication between the interior of the flush tank and the ventilating system, said overflow seal means comprising an upright U-shaped conduit having one leg in communication with the interior of the flush tank and the other leg with said ventilator seal and with the inlet of said overflow conduit, crossover means extending between the ventilator seal and overflow seal means and having conducting means extending below the elevation of the inlet of said overflow conduit and providing a path for fluid flow from the ventilator seal to the overflow seal means, and a refill conduit communicating with and supplying water to said ventilator seal such that when the latter is filled, the fluid flows via said conducting means to fill the overflow seal means and when the latter is filled to thereafter overflow through the inlet of the overflow conduit to fill said seal trap in the water closet bowl.

10

7. In combination with a ventilating system as set forth in claim 6 wherein said refill conduit is connected to said ventilator seal below the normal operating water level of the flush tank thereby insuring that the ventilator seal will fill with water from the flush tank should the refill conduit be inadvertently disconnected from the ventilator seal.
